CLAIM

The ornamental design for a display screen with graphical user interface of a gaming machine as shown and described.

DESCRIPTION

FIG. 1 is a front view of a display screen with graphical user interface of a gaming machine showing our new design; and, FIG. 2 is a front view of an alternate embodiment of a display screen with graphical user interface of a gaming machine showing our new design.

The outermost broken lines showing the display screen form no part of the claimed design. The remaining broken lines showing portions of the graphical user interface form no part of the claimed design.

1 Claim, 2 Drawing Sheets
